UNITED STATES PATENT OFFICE.

JAMES E. C. SWANN, OF VIRGINIA BEACH, VIRGINIA.

COMMUTATION-BOOK.

1,353,189.

Specification of Letters Patent. Patented Sept. 21, 1920.

Application filed March 8, 1917. Serial No. 153,344.

To all whom it may concern:

Be it known that I, JAMES E. C. SWANN, a citizen of the United States, and resident of Virginia Beach, in the county of 5 Princess Anne and State of Virginia, have invented certain new and useful Improvements in Commutation-Books, of which the following is a specification.

This invention relates to new and useful 10 improvements in tickets adapted for use on any system of transportation, and more particularly to commutation books which are so constructed that manipulation of the tickets by either the passenger or conductor 15 is prevented.

Another object of the invention is to provide a commutation book of this character which is provided with a plurality of rows 20 of trip tickets, and identification tickets, disposed directly beneath the trip tickets, the trip tickets being detachable whereby a receipt is provided when the fare has been taken which prevents any argument between the passenger and conductor as to whether 25 or not the fare has been collected for that trip. These tickets may be printed on rows of flexible, or stiffened paper, although preferably the trip tickets are printed on flexible paper, while the identification tickets disposed beneath the same are printed on stiffened paper, thus providing alternate rows of 30 flexible and stiffened leaves.

A further object of the invention is to provide a device of this character which is 35 easily and simply constructed, inexpensive to manufacture, and one which will be very efficient in operation.

With these and numerous other objects in view my invention consists of the novel features of construction, combination and arrangement of parts which will be herein referred to and more particularly pointed out in the specification and claim.

In the accompanying drawing:

45 Figure 1 is a perspective view of the book partly opened, showing one strip of the trip tickets, with the lower ticket removed to show the identification ticket disposed beneath the same, and

50 Fig. 2 is a transverse section through one of the rows of identification and trip tickets, showing that the trip tickets are attached to the identification tickets along the one edge.

In describing my invention I shall refer to 55 the drawing in which similar reference characters designate corresponding parts

throughout the several views. The front and back covers 1 and 2 of the commutation book may be formed of any desired material such as is ordinarily used in devices of this 60 character, and which are secured together at one end by any desired type of binding means, such as is illustrated at 3. Secured between the covers of this book are the trip and identification tickets, which comprise a 65 plurality of leaves being alternately flexible and stiffened, for a purpose to be hereinafter more fully described. These leaves however may be all flexible, or all stiffened if desired.

For the sake of brevity I will only specifically describe one of the rows of adjacent trip and identification tickets, as the other rows of tickets are substantially alike throughout the book. The book may be provided with any number of leaves according 70 to the number of trips designated thereon.

The trip tickets 4, are printed on a sheet of flexible material 5, which is provided with a plurality of transversely extending perforations 6, that separate the tickets and 80 have serial numbers printed or stamped thereon as at 5'. These tickets are preferably eight in number, as shown in the accompanying drawing, although any number may be printed on a sheet as desired. Dis- 85 posed directly beneath the flexible sheet of trip tickets is a row of identification tickets 7 having serial numbers 7' printed or stamped thereon corresponding to the serial numbers of the adjacent trip tickets, said 90 tickets being printed on some type of stiffening material, preferably pasteboard 8, and which tickets are not detachably connected with each other. In other words, the trip ticket 4 and the identification tickets 7 are 95 provided with serial numbers common to the alining or adjacent tickets. These rows of identification tickets if desired may be perforated at their upper edge, where the same are secured in the book, so that after 100 the row of trip tickets has been used, the identification tickets may be removed, so that a new row of superposed tickets may be in position for use. The trip and identification tickets are provided with numbers cor- 105 responding with the number of the book, so that the same may be readily identified. The superposed rows of trip and identification tickets are attached adjacent one of their side edges as shown at 9, by pasting, 110 folding, clipping, sewing, or any other desired manner. This attachment is disposed

at only one edge of the ticket, so that the trip ticket is easily removable from the identification row of tickets disposed directly beneath the same. The rows of tickets may 5 have either side edge attached as desired.

The outside of the front cover of the book shows the purpose of the same, while on the inside of said cover is printed a contract between the railroad company and the passenger who purchases the book, and the signature and address of the purchaser as at 9'. It further shows the designation of the book. If desired the book may be provided with a pair of fly leaves 10, the first 10 fly leaf which is the agent's stub, is also dated and signed by purchaser with address, and is detached by agent when book is sold and forwarded to the auditing department. The second fly leaf is the conductor's stub 15 which is detached by him for first transportation, thus showing the movement of the book. In use the trip ticket with the identification slip beneath the same is honored by the conductor and is punched before detaching the trip ticket from the identification slip. When the row of trip tickets is 20 used, the last ticket thereon is detached with the entire row of identification tickets, and is forwarded by the conductor with his ticket returns to the auditor. The book 25 when all coupons and identification checks have been detached will be accepted by the conductor for one passage, and the same will be registered, punched and forwarded to the auditing department of the railroad 30 company. The tickets of this type of book are void if detached by passenger or purchaser, as there could be no record or identification check, and if such detached tickets 35 should be honored by the conductor there would be a clear record showing that the conductor was not carrying out his instructions, and the purchaser violating his contract with the railroad company under 40

which the book was purchased by him. This 45 type of commutation book shows the exact number of transportations to both passenger and conductor, and the direction the book is moving by the conductor's punch mark. It also provides a receipt when fare has been 50 taken which prevents any question as to whether the passenger's fare has been already collected for that trip.

As has been hereinbefore stated the leaves of the book may be formed of alternate flexible 55 and stiffened material, but if desired, all of the leaves may be stiffened, or flexible. The foregoing description of the construction and operation of this commutation book fully explains the manner of applying the 60 same to use and the operation thereof, and it will be seen that I have provided a simple and efficient means for carrying out the objects of this invention.

What I claim as my invention, and desire 70 to secure by Letters Patent is:—

A commutation book comprising sheets of trip tickets detachably connected each with the others and each having printed thereon distinguishing indicia, identification sheets 75 of heavier paper than the paper forming the trip ticket sheets disposed therebetween and detachable from the book only in their entirety, the portions of the identification sheets subjacent to each of the trip tickets 80 having identification indicia printed thereon identical with the identification indicia on the respective trip tickets and adapted to receive a conductor's punch mark at the same time the trip ticket is punched and detached, 85 and each of the trip ticket sheets being detachably connected along one side edge to the subjacent identification sheet to prevent removal and use of the trip ticket without detection. 90

In testimony whereof, I affix my signature hereto.

JAMES E. C. SWANN.
